UNITED STATES PATENT OFFICE.

MAKARIY DERESHUK, OF KINSMAN, OHIO.

DESIGN FOR A PUZZLE TOY.

Application filed January 7, 1922. Serial No. 106. Term of patent 3½ years.

To all whom it may concern:

Be it known that I, MAKARIY DERESHUK, citizen of Russia, residing at Kinsman, in the county of Trumbull and State of Ohio, have invented a new, original, and ornamental Design for a Puzzle Toy, of which the following is a specification, reference being had to the accompanying drawing, forming part thereof.

The figure is a perspective view of a puzzle toy, showing my new design.

I claim:

The ornamental design for a puzzle toy, as shown.

In testimony whereof I have affixed my signature.

MAKARIY DERESHUK.
